(57) **CLAIM**

The ornamental design for a gun support bracket, as shown and described.

DESCRIPTION

FIG. 1 is a perspective view of the gun support bracket;
FIG. 2 is a front view of the gun support bracket;
FIG. 3 is a back view of the gun support bracket;
FIG. 4 is a side view of the gun support bracket;
FIG. 5 is a top view of the gun support bracket; and,
FIG. 6 is a perspective view of the gun support bracket in an
environment secured to a vehicle.
The broken line showing depicts environmental subject matter
only and forms no part of the claimed design.
